UNITED STATES PATENT OFFICE.

WILLIAM TIMMIS, OF PITTSBURG, PENNSYLVANIA.

WINDOW-CHAIR.

SPECIFICATION forming part of Letters Patent No. 593,501, dated November 9, 1897.

Application filed July 28, 1897. Serial No. 646,197. (No model.)

To all whom it may concern:

Be it known that I, WILLIAM TIMMIS, of Pittsburgh, in the county of Allegheny and State of Pennsylvania, have invented a new and Improved Window-Chair, of which the following is a specification.

My invention is an improvement in the class of so-called "window-chairs" or portable platforms which are specially adapted for use as temporary supports in window-cleaning. The improvement is embodied in the construction and combination of parts hereinafter described, whereby I produce a window-chair adapted to be folded for placing it in or removing it from a window, and which when expanded and duly adjusted forms a firm and stable support.

In the accompanying drawings, Figure 1 is a perspective view of my preferred construction of window-chair, and Fig. 2 is a perspective view showing the chair partly folded or adjusted for passing it through a window-opening. Fig. 3 is a view showing a modification.

The skeleton frame of the chair proper is attached to and supported in working position by two parallel bars 1, whose inner ends project through slots in a retaining-bar 2, arranged on the window-sill 3, with its ends bearing against the sides of the casing 4, as shown in Fig. 1. The said bars 1 may be adjusted lengthwise, as required, and are secured by pins 5, that pass through them and the retaining-bar 2. The latter is divided transversely and thus composed of two equal parts, which are connected by a hinge 6 and locked in alinement by a sliding bolt 7 when in use.

The base or bottom of the chair proper is composed of flat parallel lengthwise bars 8 and right-angular connecting-bars 9 9', all of which are riveted or bolted together. The said bars 8 are divided transversely and the two equal parts connected by hinges 10 at their inner ends and also provided with sliding bolts 11, like the retaining-bar 2 before described.

The angle-bars 9 and 9' are arranged with their shorter arms vertical, and these are connected by flexible parallel strips 12, preferably composed of leather, although canvas, woven wire, chains, or other substitutes may be employed. Said strips 12 are secured to

the angle-bars by rivets, screws, or bolts, and thus extend along the outer side of the chair, so as to form a side guard for preventing a person from accidentally falling off the chair. As an end guard I employ a rigid bar 13, which connects the vertical arms of the outer angle-bars 9', as shown.

I thus produce a window-chair whose frame proper is composed of rigid pieces or parts and which is at the same time adapted to be folded and partly collapsed by reason of the arrangement of the hinges 6 and 10 and the flexible strips 12 aforesaid—that is to say, by drawing back the bolts 7 and 11 it is apparent the bars 2 and 8 may be bent upward at the middle, as shown in Fig. 2, thus narrowing the width of the chair as a whole, so that it may be put through window-openings. It will be seen that this construction enables a wide chair to be used in a window that would otherwise be too narrow, and in fact adapts it for use in windows of different widths.

The retaining-bar 2 is provided with a series of slots spaced equidistantly to permit it to be adjusted endwise whenever required to accommodate it to windows which are close to a wall.

In Fig. 3 I show a retaining-bar 2' and chair-bottom bars 8', provided with hinges 6' and 10, which are reversed from the position shown in the other figures, so that the chair may be folded upward instead of downward. In this instance the arrangement of the hinges forms practically so many rule-joints which resist pressure in a downward direction, so that the use of sliding bolts is less required than in the case first described.

What I claim is—

1. The improved window-chair, composed of the retaining-bar formed of two sections, hinged together, and a device for holding them in rigid alinement, the two parallel bars 1, and the transverse bottom bars 8, attached to said bars 1 and formed of hinged foldable sections having locking devices, as shown and described.

2. The improved window-chair comprising the retaining-bar formed of two parts whose inner ends are hinged together, the chair-frame proper formed of bottom bars that are similarly composed of parts hinged together endwise, one or more flexible guard-strips,

and rigid transverse bars connecting the hinged bottom bars, and supporting the said strips, and parallel chair-supporting bars that are attached to the retaining-bar, substantially as shown and described.

3. The combination, with the chair proper, comprising two rigid frame parts which are hinged together, and flexible guard-strips arranged at the front of the chair and connecting such hinged parts of parallel supporting-bars, a two-part foldable retaining-bar, and slidable bolts applied opposite the hinges to hold the parts in due alignment when in use, as shown and described.

4. The improved window-chair composed of the chair-frame proper, having bottom bars composed of bars connected endwise by hinges that fold downward, and flexible guard-strips extending across the outer side of the frame, the parallel supporting-bars, and the retaining-bar whose two parts are connected by hinges folding downward, as shown and described.

WILLIAM TIMMIS.
